UNITED STATES PATENT OFFICE.

LESTER THAYER, OF WINTHROP, MASSACHUSETTS, ASSIGNOR TO FORBES LITHOGRAPH MANUFACTURING COMPANY, OF BOSTON, MASSACHUSETTS, A CORPORATION OF MASSACHUSETTS.

PRESS.

Application filed June 1, 1922, Serial No. 565,215. Renewed January 6, 1926.

To all whom it may concern:

Be it known that I, LESTER THAYER, a citizen of the United States, and a resident of Winthrop, county of Suffolk, State of Massachusetts, have invented an Improvement in a Press, of which the following description, in connection with the accompanying drawings, is a specification, like characters on the drawings representing like parts.

My invention relates to presses for printing and lithographing and particularly but not exclusively to those for printing on cardboard sheets the impressions for a plurality of cartons.

In the manufacture of cartons having printed or lithographed exteriors, it is usual to print or lithograph a number of cartons at a time on sheets of greater size than can be handled by the machine employed for cutting or stamping out and scoring the cartons, which necessitates the sheet being divided into smaller sheets before subjecting it to the operation of the cutting and scoring machine. Heretofore the dividing of the sheets has either been done in separate machines or by means of auxiliary devices attached to the press, in either case the dividing into smaller sheets being done after the sheet is printed. For fine classes of work it has been found that both of these methods fail to permit the cutting and scoring machine to cut and score the sheet in proper relation to the printed or lithographed matter, due to the inaccuracies in the attachments to the presses for dividing the sheet, and in cases where the dividing is done in a separate machine, due to the expansion and contraction of the sheets when subjected to the atmosphere during the time between printing and presentation to the machine for dividing them.

According to my invention the sheets are split into smaller sheets in the presses simultaneously with the printing or lithographing in such manner that an exact relation is preserved between the edges of the portions of the sheet so divided and the printed

and lithographed matter. My invention may also be applied to presses which partially split the sheet as for example when a perforated line is desired or the sheet is slotted to prepare it for an embossing press.

My invention will be best understood from the following description when read in light of the accompanying drawings of several specific embodiments of my invention selected for illustration, while the scope of my invention will be more particularly pointed out in the appended claims.

In the drawings:

Fig. 1 shows more or less diagrammatically my invention applied to a flat bed press.

Fig. 2 shows a press constructed according to Fig. 1 looking from the left with the bed in section.

Fig. 3 shows a detail of the impression cylinder for the machine constructed according to Fig. 1.

Fig. 4 is a perspective view of the knife.

Fig. 5 more or less diagrammatically illustrates my invention applied to a form of rotary press.

Fig. 6 is a perspective of a fragment of the knife employed in the press according to Fig. 5; and

Figs. 7 and 8 respectively illustrate ways of securing the knife to the plate cylinder in the press constructed according to Fig. 5.

Referring particularly to Figs. 1 to 4 of the drawings, which illustrate the preferred form of my invention when applied to a flat bed press, I have indicated the bed 1 as mounted for reciprocation on the track 3, while above the bed I have shown the impression cylinder 5, which as will be understood by those skilled in the art is caused to rotate when the bed reciprocates. In Fig. 1 I have indicated the feeding mechanism for the sheets diagrammatically at 7 and the delivery mechanism for the sheets diagrammatically at 9, the sheets as is common in this type of machine being fed by the impression cylinder in the direction of the

arrow 11, whence it passes between the impression cylinder and bed and is finally delivered in the direction of the arrow 13 to the delivery mechanism 9. As will be understood, when the sheet passes between the bed and the impression cylinder the sheet is printed or lithographed.

Referring to Fig. 2 I have indicated the plates which apply the color or printed matter to the sheet at 15, said plates being supported on the usual blocks 17. On the bed I further mount the knife 19 supported by the blocks 17, which knife as is illustrated in Fig. 4 is in the form of a bar or narrow metal strip having the cutting edge 21. If desired however the knife may take the form of that hereinafter described in connection with the rotary press. Co-operating with the knife and serving as a platen therefor is the band 23, preferably constructed of a flexible strip of steel, which encircles the impression cylinder. About that portion of the impression cylinder which faces the plates during the printing operation I provide the packing 25, the band in a manner hereinafter explained being caused to have its outer surface substantially flush with the outer surface of the packing.

For holding the band 23 in position the ends are bent over and if necessary secured to blocks 27, the band and the blocks being perforated to receive the oppositely screw-threaded ends of the turn-buckle 29, the perforations 31 of the blocks being screw-threaded to receive the turn-buckle and the turn-buckle intermediate its ends being provided with the nut 33 whereby the turn-buckle may be operated.

For adjusting the band 23 radially of the impression cylinder to bring the outer surface of the band in the proper relation with the knife to compensate for wear of the cutting edge of the knife and to bring the outer surface of the band substantially flush with the outer surface of the packing, I insert shims 35 of paper or other suitable material between the impression cylinder and the band, the turn-buckle permitting the band to be loosened and adjusted for this purpose. As will be understood the shims of paper provide a yielding backing which will cause the band 23 to be yieldingly supported against the action of the paper and knife.

In Figs. 1 and 2 I have indicated one knife and one band with a divided packing, portions of which are situated at opposite sides of the band. It will be understood, however, that I may employ any number of knives and bands for splitting the sheet into as many parts as necessary.

In Fig. 5 I have illustrated a rotary press wherein 39 is the feed cylinder, 41 an impression cylinder, 43 the plate cylinder and

45 either a transfer cylinder for another 65 pair of impression and plate cylinders or a delivery cylinder. It will be understood by those skilled in the art the sheets to be printed and split are fed to the feed cylinder as indicated by the arrows 46 and are discharged from the cylinder as indicated by the arrows 47. When my invention is applied to a rotary press the knife and the knife platen are carried by the impression and plate cylinders, and in cases where there 75 are more than one impression and plate cylinder, are carried by those doing the final printing operation.

In Fig. 5 I have indicated the knife as carried by the plate cylinder 43 and the platen for the knife as carried by the impression cylinder 41. In this form of my invention the knife, as is illustrated by Fig. 6 is provided with a cutting edge 48 and a base 49, which base supports the knife on the cylinder in such manner as to prevent it from tilting. Preferably, the band is of flexible material in order that it may be made to readily conform to the cylinder and to be adjusted thereon when necessary.

The knife may be secured to the cylinder in any suitable manner. In Figs. 6 and 7, the base of the knife is shown as provided with bevelled edges 51 which are engaged by the clips 53 held to the cylinder by means of screws 55 engaging nuts 57 having bevelled sides engaging the bevelled sides 59 of the slots 61 formed in the cylinder. The slots and clips may be those commonly used with plate cylinders for holding the plates 100 in position and it is believed need not be further described.

If desired, the knife may be held on the cylinder and particularly with those types of cylinders which are not provided with slots by means of screws, the base 49 of the knife for this purpose being provided with the countersunk screw holes 63.

Fig. 8 shows a modified way of securing the knife in position. As illustrated the plate cylinder is provided with the recesses 65, the side of one of which is provided with the pin 67, while the end of the knife is bent down as is indicated at 69 to enter the recess and is provided with a perforation which the pin enters. At its opposite end the knife is bent about a block 27, similar to that described in connection with the band 23 for the flat bed press, the screw-threaded perforation of the block receiving a screw 70, the end of which enters the recess or "spot" 71 formed in the wall of the recess 65. By this means the knife may be placed under tension and firmly secured to the cylinder.

The platen for the knife in the rotary press, as shown by Fig. 5, is held on the impression cylinder and takes the form of the

band 23 mounted in exactly the same manner as disclosed in connection with the flat bed press illustrated by Figs. 1 and 2.

In rotary presses as well as in the flat bed press I prefer to mount the knife on the plate carrying member. It, however, is possible to reverse this arrangement and carry the knife on the impression cylinder, which reversed arrangement is particularly applicable to presses with printing or color cylinders having a continuous plate of zinc, the surface of which is prepared for applying print or color.

The forms of my invention exemplified by Figs. 1, 2 and 8 are more specifically claimed in my copending applications Serial Nos. 652,335 and 652,336, filed July 18, 1923. It will be understood however that I am not limited to the illustrative forms of my invention herein described, but that wide deviations may be made therefrom without departing from the spirit of my invention.

Claims—

1. In a lithographing press, the combination with a rotary impression member for the sheet operated upon and a plate carrying member, of a knife for splitting the sheet transversely to the axis of said impression member simultaneously with the applying of print thereto, said knife being carried by one of said members for acting on the sheet intermediate the boundaries of the region thereof printed, and a platen for the knife adjustable toward or away from the cutting edge of said knife carried by the other of said members.

2. In a lithographing press, the combination with a rotary impression member for the sheet operated upon and a plate carrying member, of a knife set up among the plates on said plate carrying member with its cutting edge arranged for splitting the sheet transversely to the axis of said impression member intermediate the boundaries of the region of the sheet printed simultaneously with the applying of print thereto, a platen for the knife carried by said impression member, and means for adjusting said platen and knife toward or away from each other.

3. In a press, the combination with a rotary impression member for the sheet operated upon and a cooperating print applying member, of a knife carried by the print applying member for splitting the sheet simultaneously with the applying of print thereto, and a yieldingly supported platen for the knife carried by the impression member.

4. In a press, the combination with a rotary impression member for the sheet operated upon and a cooperating print applying member, of a knife carried by the print applying member for splitting the sheet intermediate the boundaries of the region

thereof printed simultaneously with the applying of print thereto, a radially adjustable platen for the knife bent about said impression member, and tension means for said platen.

5. In a press having a rotary print applying cylinder and a cooperating rotary impression cylinder and means for splitting sheets fed between said cylinders in the direction of feed simultaneously with the printing thereof, said means for splitting the sheets comprising a knife member on one cylinder and a cooperating platen member on the other cylinder, and a packing on one cylinder supporting one of said members.

6. In a press having a rotary print applying cylinder and a cooperating rotary impression cylinder, and a knife carried by one of said cylinders and a cooperating platen carried by the other of said cylinders intermediate their lengths for splitting sheets in the direction in which said sheets are fed simultaneously with the applying of print thereto, and a packing on the cylinder carrying said platen for supporting said platen.

7. In a lithographing press having a rotary print applying cylinder and a cooperating rotary impression cylinder, and a knife carried by said print applying cylinder and a cooperating platen carried by the impression cylinder intermediate their length for splitting sheets in the direction in which said sheets are fed simultaneously with the applying of print thereto, and a packing on said impression cylinder for supporting said platen.

8. In a lithographing press having a rotary impression cylinder and a cooperating plate carrying cylinder, a knife set up among said plates, a band serving as a platen for said knife, said band being bent about said impression cylinder, and tension means for said band.

9. In a lithographing press having a rotary impression cylinder and a cooperating plate carrying cylinder, a knife set up among said plates, a strip extending over the surface of said impression cylinder and serving as a platen for said knife, and means for adjusting said strip and knife relatively to each other radially of said impression cylinder.

10. In a lithographing press having a rotary plate cylinder provided with clip holding recesses, clips adjustably mounted in said recesses, and a knife carried by said cylinder and provided with portions for engagement with said clips.

11. In a lithographing press having a rotary plate cylinder provided with clip holding recesses, clips adjustably mounted in said recesses, and a knife carried by said cylinder and provided with a base having

bevelled edges for engagement with said clips.

12. In a lithographing press having a rotary plate cylinder provided with clip holding recesses, clips adjustably mounted in said recesses, and a flexible knife bent about said cylinder and provided with portions for engagement with said clips.

13. In a lithographing press having a rotary plate cylinder provided with clip holding recesses, clips adjustably mounted in said recesses, and a flexible knife bent about said cylinder and provided with a base having bevelled edges for engagement with said clips.

14. In a press, a rotary impression cylinder and a cooperating plate carrying member, packing carried by said impression cylinder, a metal strip carried intermediate the length of said impression cylinder and having its outer surface substantially flush with the outer surface of said packing, and a knife carried by said plate member and cooperating with said strip to split the sheets fed to said press simultaneously with the printing of said sheets. 20 25

In testimony whereof, I have signed my name to this specification.

LESTER THAYER.

Certificate of Correction.

It is hereby certified that in Letters Patent No. 1,579,180, granted March 30, 1926, upon the application of Lester Thayer, of Winthrop, Massachusetts, for an improvement in "Presses," an error appears in the printed specification requiring correction as follows: Page 3, line 39, claim 2, before the word "plate" insert the word *cooperating*; and that the said Letters Patent should be read with this correction therein that the same may conform to the record of the case in the Patent Office.

Signed and sealed this 18th day of May, A. D. 1926.

[**SEAL.**]

M. J. MOORE,
Acting Commissioner of Patents.
